UNITED STATES PATENT OFFICE.

CHARLES M. MEANS, OF PUNXSUTAWNEY, PENNSYLVANIA, ASSIGNOR TO
H. W. JOHNS-MANVILLE COMPANY, A CORPORATION OF NEW YORK.

SECTION-INSULATOR FOR TROLLEY-ROADS.

No. 835,909.

Specification of Letters Patent.

Patented Nov. 13, 1906.

Application filed April 9, 1906. Serial No. 310,690.

To all whom it may concern:

Be it known that I, CHARLES M. MEANS, a citizen of the United States of America, and a resident of Punxsutawney, county of Jefferson, State of Pennsylvania, have invented certain new and useful Improvements in Section-Insulators for Trolley-Roads, of which the following is a specification.

My invention relates to section-insulators for electric trolley-roads in general; and it more specifically consists of an improved section-insulator for use in mines and tunnels.

The ordinary section-insulator used on surface trolley-roads has its insulating portion formed of wood or fiber and exposed. When such an apparatus is used in a mine or tunnel, the constant dripping of water on it soon saturates it, destroys its insulating properties, and then disintegrates the whole apparatus.

These section-insulators are also generally made of such form that when any defect in the insulation occurs the current leaks to the adjoining section rather than to the ground. This is a source of danger in mines, as the wires are strung only four or five feet above

the rails and men are required to work along and under this wire at all times. In minework the section-insulator must be attached to the rocky roof of the tunnel. This it is difficult to do with any of the standard forms of section-insulator. Standard practice in mining requires the frequent insertion of section-insulators in trolley-wires after they have been strung. It is difficult to do this

with the ordinary form of section-insulator without having the wire slack. Such slackening of the wire is particularly objectionable in minework, as the wire is only a few inches below the tunnel-roof, and if slackened is pushed up into contact therewith by the trolley-wheel. I have invented a form of section-insulator which avoids all these difficulties and has other advantages hereinafter to be pointed out. The best form of apparatus embodying my invention at present known to me is illustrated in the accompanying sheet of drawings, in which—

Figure 1 is a side elevation of my improved section-insulator. Fig. 2 is a plan view, and Fig. 3 a detail view in section. Fig. 4 is a detail cross-section taken on line 4-4 of Fig. 1 looking in the direction of the arrow.

Throughout the drawings like reference figures indicate like parts.

1 is the base-plate or bed-plate, which may 55 be made of malleable cast-iron. From this are suspended a series of insulation-bells 2 2 by means of screw-bolts 3 3 and washers 4 4, &c. In each of these bells is forced a mass of molded mica or other molded insulation, 60 (shown at 5 in Fig. 3.) This incloses and retains in place a screw-bolt 6, which is screwed into a socket in the upper portion of one of the wire-clamps 7 7. Each of said clamps has a grooved channel 8 in its side for the 65 reception of the trolley-wire and a laterally-projecting lip 9 to guide the same in introduction.

10 10 are set-screws in the clamp for holding the wire in position, and 11 is a channelled lug on the end of each, provided with a set-screw 12, by which a feed-wire may be connected to the clamp in the well-known manner.

13 is a hole through which a bolt or other 75 convenient fastening means may be passed in order to attach the section-insulator to the roof of the tunnel or any convenient overhead support.

In operating my invention the wire-clamps 80 are preferably placed over the wire when the latter is in position, and the set-screws 12 12 are screwed down, so as to retain the wire in its position. The wire may then be cut between the two clamps 7 7, thus insulating the 85 two sections of the trolley-wire. When the progress of the minework renders it desirable to take out the section-insulator, the wire can be spliced by using a short splicing-sleeve and the insulator inserted at another 90 point farther down the tunnel or heading. The air-gap between the adjacent ends of the wire-clamps being slightly less than the air-gap between said clamp and the insulating-bell, any arc caused by a rapidly-passing trolley-wheel will not jump to the adjacent insulator-bell, and so there is no tendency of the arc to melt and destroy the molded insulating material. The molded insulating material is entirely protected from the action of 95 dripping water, and if the moisture in the air should deposit a conducting-film on the under side of the molded insulating material any current which thus leaked away would be immediately conducted by the foundation-plate 1 to the mine-roof instead of leaking across to the other section of the wire and charging the same, to the danger of men who

100

105

were working along the advance section. The parts are easily assembled or taken down and replaced if any be broken or damaged. Each clamp having two supports and 5 each support being embedded in the molded insulating material in a separate bell, a much greater resistance is offered to any force tending to twist the clamp than is the case with prior constructions. Where such hangers 10 have been supported from a single bell where the clamp has but one support embedded in molded material, a twisting force easily turns the support in its socket and breaks it free from the surrounding molded material and 15 begins the rapid destruction of the entire device.

The advantages of my invention comprise its imperviousness to the action of moisture, being composed entirely of metal 20 and molded insulation, the protection of the insulating material from water as far as possible, the ease of its application to a wire already strung, and the avoidance of any necessity for cutting out any considerable section 25 of said wire, with the result that the same can be easily spliced when the section-insulator is removed, and other features of novelty hereinbefore referred to.

It is evident, of course, that various changes 30 could be made in the details of construction shown and described without departing from the spirit and scope of my invention so long as the essential principles of operation hereinbefore referred to be preserved in 35 whole or in part.

Having therefore described my invention, I claim—

1. A section-insulator for electric trolley-roads which comprises in combination, a 40 metal bed-piece, a series of metal bells depending therefrom, a body of molded insulating material in each of said bells, and two.

wire-clamps arranged in line, each clamp having two supports embedded in said molded insulating material, each support being 45 embedded in a separate bell.

2. A section-insulator for electric trolley-roads which comprises in combination a metal bed-piece, a series of metal bells depending therefrom, a body of molded insulating material in each of said bells, and two wire-clamps arranged in line, each clamp having two supports embedded in said molded insulating material, each support being 50 embedded in a separate bell, the inner ends 55 of said wire-clamps being separated by a short air-gap.

3. A section-insulator for electric trolley-roads which comprises in combination a main frame, and a pair of wire-clamps supported thereby and insulated one from the other, each of said clamps having a grooved channel in its side for reception of the trolley-wire, the upper portion of each channel being provided with set-screws and the under 60 portion with a horizontally-projecting lip.

4. A section-insulator for electric trolley-roads which comprises in combination a metal bed-piece, a series of metal bells depending therefrom, a body of molded insulating material in each of said bells, and two wire-clamps arranged in line and having supports embedded in said molded insulating material, said clamps having their inner ends 70 separated one from another by a short air-gap, but separated from the nearest bell by a greater air-gap.

Signed at Punxsutawney, Pennsylvania, this 31st day of March, 1906.

CHARLES M. MEANS.
